ATTORNEY

UNITED STATES PATENT OFFICE

FRANK H. HALL, OF BRADFORD, PENNSYLVANIA, ASSIGNOR TO BOVAIRD & COMPANY, OF BRADFORD, PENNSYLVANIA, A COPARTNERSHIP COMPOSED OF JOSEPH H. BOVAIRD, GEORGE W. BOVAIRD, AND MARY B. DOWNS

SUCKER-ROD TURNER

Application filed July 16, 1928. Serial No. 292,978.

My invention relates to a sucker or polish rod particularly pertaining to oil wells.

In operating oil wells where wax from the crude oil accumulates, and although sometimes the accumulation is slow, frequently the wax in time clogs the tubing so that the sucker or polish rod cannot move up and down freely, or, as frequently happens, cannot be moved at all. This necessitates pulling the rod out of the tubing, and at times the rod becomes fast in the tubing so that both rod and tubing have to be pulled at one time.

The general object of my invention is to provide a novel means for preventing the accumulation of wax in the tubing by causing a turning movement to be imparted to the polish rod, thus either keeping the wax pumped out with the oil, or in case the wax has accumulated, loosening the same so that the sucker rod can be operated freely.

Characteristic features of the invention are that the turning means is associated with an oil well pumping jack; the sucker rod is turned with the down stroke of the polish rod and by means of a ratchet; the ratchet is made in halves so that it can be clamped on; the pawl is adapted to be thrown out while the pumping jack is operating; vertical adjustment of the ratchet wheel is provided for so that by moving it up or down on the polish rod the motioning part of the wheel by the operating pawl is varied; the gravity method is employed for maintaining the pawl with the ratchet; the device may be placed either above the walking beam as illustrated in the drawings, or below the same; the ratchet is attached to the polish rod while the operating mechanism of the ratchet is attached to the jack.

The nature of my invention and the distinguishing features in which the invention resides, as well as their advantages, will clearly appear as the description proceeds.

Reference is to be had to the accompanying drawings forming a part of this specification, it being understood that the drawings are merely illustrative of one example of the invention.

Figure 1 is a side elevation of a sucker rod turner and pumping jack, part of the as-

semblage being broken away and in section; Figure 2 is an enlarged horizontal section on the line 2—2 of Figure 1;

Figure 3 is a detail in vertical section on an enlarged scale as indicated by the line 3—3 in Figure 1;

Figure 4 is a section on the line 4—4 of Figure 3.

In the illustrated embodiment of my invention the numeral 10 indicates a channel beam sill from which a post 11 rises strengthened by a brace 12, said post and brace converging at the upper end to receive a pivot 13 of the channel bar walking beam 14. A jack designated generally by the numeral 15 is pivoted below as at 18 to sill 10 and is operated by a reciprocating rod 16 actuated from any source of power, not shown. The numeral 17 designates a link connecting the jack with the walking beam 14, and the numeral 19 indicates the lower end of a clamp to which the link 17 is pivoted by bolt 20. The numeral 21 indicates a sucker rod or polish rod.

In carrying out my invention a block 22 is secured by a bolt 122 to that end of the walking beam 14 opposite the pivot 13 of said beam, and to said block 22 is secured by a bolt 23 a bedplate 24 which is seated on the beam 14 and which is provided with a guide 25 for the polish rod 21, and has trunnions 26 seated on the bedplate 24 as a bearing. The numeral 27 indicates the polish rod clamp.

In accordance with my invention a plate 28 is suitably fastened for example by bolt 23 to the bedplate 24, and has upwardly projecting ears 29 between which is secured the lower end of an upwardly extending pawl 31 through the medium of bolt 30 or other pivot means. The pawl 31 engages a horizontally disposed ratchet wheel 32 held to the polish rod 21 by clamp 34, said ratchet wheel being made in halves. On said pawl 31 on that side toward the polish rod is a balance arm 33 tending to maintain the pawl in engagement with the ratchet wheel 32.

By raising or lowering the ratchet wheel 32 on the polish rod 21 it will be readily understood that the ratchet wheel will be engaged by a point on the pawl 31 more or less

distant from the pivot 30 to vary the turning movement imparted to the ratchet wheel 32 by the pawl 31.

In operation the jack frame is vibrated by the rod 16 or otherwise, the jack through the medium of the link 17 vertically vibrates the walking beam 14 on its pivot 13, and as the beam 14 moves downwardly the engagement of the pawl 31 maintained by the weight arm 33 will cause a turning movement to be imparted to the ratchet wheel 32, and, hence, a turning movement will be imparted to the polish rod 21 for preventing the accumulation of wax, or for loosening any wax that may be accumulated.

As the walking beam is moved to the vertical dot-and-dash line position in Figure 1, pawl 31 will slip over the ratchet wheel 32 ready for imparting a turning movement to said ratchet wheel and the polish rod with the next downward stroke of the walking beam.

I would state furthermore that while the illustrated example constitutes a practical embodiment of my invention, I do not limit myself to the exact details herein illustrated, since, manifestly, the same can be considerably varied without departure from the spirit of the invention as defined in the appended claims.

30 I claim:

1. In a device of the class described, a walking beam, means for swinging the walking beam, a polish rod, a guide for the polish rod having trunnions mounted on the free end of walking beam, a ratchet wheel on the upper end of the polish rod, a laterally extending member secured to the free end of the walking beam and having an angular end, and a pawl pivoted to the angular end of said member and extending upwardly for engagement with the ratchet wheel, said pawl having an arm between its pivot and the point of engagement with the ratchet wheel for holding it in engagement with the ratchet wheel.

2. In a device of the character described, a walking beam, means for operating the walking beam, a polish rod, a ratchet wheel on the upper end of said rod, a plate on the upper face of the walking beam and having bearings, a guide for the polish rod having trunnions mounted in the bearings, a right angular plate secured to the first front plate with one member extending at the side of the walking beam, said member being provided on its upper face with spaced ears, and an upwardly extending pawl pivoted between said ears and adapted to engage the ratchet wheel, said pawl having means for holding it in engagement with the ratchet wheel.

FRANK H. HALL
